United States Patent Office

Des. 195,322
Patented May 28, 1963

195,322

EAR PLUG OR SIMILAR ARTICLE

George M. Hill, Los Angeles, Calif., assignor to Sigma
Engineering Co., Los Angeles, Calif., a co-partnership

Filed Apr. 10, 1961, Ser. No. 64,672

Term of patent 14 years

(Cl. D83—1)

FIG. 1.

FIG. 2.

FIG. 3.

FIG. 1 is a side elevation of an ear plug or similar article showing my new design;

FIG. 2 is an end elevation taken from the left of FIG. 1; and

FIG. 3 is an end elevation taken from the right of FIG. 1.

I claim:

The ornamental design for an ear plug or similar article, as shown.
